[57] CLAIM

The ornamental design for a network interface enclosure, substantially as shown and described.

DESCRIPTION

FIG. 1 is a front perspective view of a network interface enclosure according to our new design showing the network interface enclosure in its closed condition; FIG. 2 is a front elevational view thereof;

FIG. 3 is a rear elevational view thereof;

FIG. 4 is a right side elevational view thereof, the left side being a mirror image;

FIG. 5 is a top plan view thereof;

FIG. 6 is a bottom plan view thereof;

FIG. 7 is an exploded perspective view thereof, showing the separate halves;

FIG. 8 is a front elevational view of the base portion thereof;

FIG. 9 is a right side elevational view thereof;

FIG. 10 is a left side elevational view thereof;

FIG. 11 is a top plan view thereof; and

FIG. 12 is a bottom plan view thereof.
